UNITED STATES PATENT OFFICE.

EDUARD VON SALIS, OF WINTERTHUR, SWITZERLAND, ASSIGNOR TO BUSCH-SULZER BROS.-DIESEL ENGINE COMPANY, OF ST. LOUIS, MISSOURI, A CORPORATION OF MISSOURI.

FUEL-INJECTION DEVICE FOR INTERNAL-COMBUSTION ENGINES.

Application filed December 29, 1924, Serial No. 758,510, and in Switzerland January 22, 1924.
Renewed January 12, 1928.

My invention relates to an airless fuel injection device comprising an accumulator and associated means enabling it to be located at a distance from the point of injection of the fuel into the cylinder without interfering with the substantially constant and adequate high velocity of fuel injection requisite to efficient engine operation. Capability of location at a distance from the point of fuel injection means that the accumulator chamber may be placed at the most convenient and advantageous point and that, in two-cycle engines, to which the invention is especially but not exclusively applicable, the crank shaft itself may be used as the cam shaft. The invention has various features in common with the fuel injection device disclosed in the application of Edward von Salis, Serial No. 747,706, filed November 4, 1924, on which it is an improvement, but differs therefrom in respects hereinafter pointed out.

Referring to the drawing: Fig. 1 is a vertical section through the fuel injection device and related parts, the arrangement being illustrated diagrammatically as for a two cycle engine.

Fig. 2 is a vertical section of a modification in which the accumulator chamber and immediately associated structure corresponds substantially to the form of injection device shown in the co-pending case above referred to.

In the preferred form of the invention wherein it is applied to a two-cycle engine, 1 is a usual variable delivery fuel pump mounted adjacent the crank shaft 2 for operation therefrom in any suitable way, and delivering fuel to the accumulator chamber 3, in which is located the accumulator plunger 4, having an extension 5 projecting through the cap of the accumulator chamber and surrounded by the accumulator spring 6 acting upon the enlargement 7 to return the accumulator plunger. The needle valve 8 in Fig. 1, 8' in Fig. 2, controls the outlet from the accumulator chamber being in both the forms illustrated, provided with a pressure area 9 whereby it is opened by the fuel at the proper time. The accumulator spring 6, when not acting as such, tends to seat the valve, acting in Fig. 1 through lever 10

fulcrumed at 11 on the cap of the accumulator chamber and to which, as by pin 12, the extension 5 of the accumulator plunger 55 is pivotally or otherwise movably connected, the free end of the lever resting upon the end of the valve stem. It will be observed that the plunger and valve in Fig. 1 are mounted side by side, but that in Fig. 2, as 60 in the aforesaid pending application, the plunger, here a sleeve 4', is concentric with the valve 8' and closely fits the same and a cavity in the accumulator chamber, the plunger being acted upon by the accumula- 65 tor spring 6 and, through the inwardly projecting plunger cap 13 and the annular shoulder 14 on the valve stem, acting to seat the valve. This arrangement is more compact than that of Fig. 1, which, however, has the advantage of a quicker movement of the valve in closing and of applying less force to the valve in this operation, owing to the decreased leverage, which provides a somewhat softer valve action. In 70 both forms of the device the valve is temporarily blocked against opening by mechanical means, as the bell-crank 15, the end 16 of one of whose arms is forced down by the spring 17 into contact with a collar or 80 enlargement 18 on the stem of the valve 8 in Fig. 1 and against the end of the stem of the valve 8' in Fig. 2, thereby seating it save when the other arm of the lever bearing the cam roller 19 is actuated by cam 20 85

on the crank shaft or other cam shaft 2, at which time, the valve being unblocked, fuel pressure on its area 9 opens it. The valve may be unblocked and the pump may be operated, in the arrangement shown in 90 Fig. 1, from the crank shaft to the engine which is assumed to be a two-cycle engine, thus enabling the usual special cam shaft to be dispensed with. This convenient location is made possible by the provision of a fuel injection valve 21 mounted at or on the cylinder 22, and preferably of a usual fuel-opened-spring-closed type as shown. The accumulator chamber is connected with this fuel injection valve by a pipe 23 of the required length. The provision in association with an accumulator of a mechanically blocked but periodically unblocked outlet 100 valve, as in the companion application above

referred to, would enable substantially constant and high fuel ejection velocity from the accumulator chamber to be maintained, and this would mean securing the desired results if the outlet of the accumulator chamber were also the engine injection opening, but in order to gain these results at a distance from the engine injection opening, the valve 21 must be provided, the pipe 23 being thus shut off from the cylinder except during fuel injection whereby it is prevented from being drained during the suction stroke of the engine and whereby also the deposit of carbon from gases which would otherwise be blown into it during the working stroke is prevented.

Both forms of the device operate as follows: When the pump delivers fuel to the accumulator chamber, the accumulator plunger is thereby forced back and the accumulator spring put under pressure the valve being thereby relieved from the effect of the accumulator spring but remaining subject to the obstructive effect of the pressure of spring 17 exerted through the bell crank until the same is operated by its cam, whereupon the charge is forcibly ejected into the pipe leading to the fuel injection nozzle at the cylinder and by its pressure opens the valve 21 and injects the charge at high and substantially constant velocity into the cylinder.

I claim:—

1. An airless fuel injection device for internal combustion engines comprising an accumulator located at a distance from the cylinder, subject to pressure of the fuel charge, and having associated therewith a fuel outlet, a blocked valve commanding said outlet, means for periodically unblocking said valve, means for operating the valve when unblocked, a pipe connecting said fuel outlet to the cylinder, and a valve automatically controlling the fuel injection nozzle on the cylinder.

2. An airless fuel injection device for internal combustion engines comprising an accumulator chamber located at a distance from the cylinder and having a fuel outlet, a blocked valve commanding said outlet, an accumulator subject to pressure of the fuel in the chamber and operatively connected to the valve, means for periodically unblocking said valve, a pipe connecting the fuel outlet of the accumulator chamber to the cylinder, and a fuel-opened-spring-closed valve controlling the fuel injection nozzle on the cylinder.

3. An airless fuel injection device for internal combustion engines comprising a pump, an accumulator chamber located at a distance from the cylinder and connected with the pump and with the fuel injection nozzle at the cylinder, an accumulator plunger subject to the pressure of the fuel

in the chamber, a blocked valve commanding the outlet from the accumulator chamber to said connections, operative connections between said accumulator plunger and valve to seat the valve, the engine crank shaft being provided with means for operating the fuel pump and for periodically unblocking said valve, and a valve at the cylinder controlling the fuel injection nozzle.

4. An airless injection device for internal combustion engines comprising an accumulator spring and plunger subject to pressure of the fuel charge, an opening through which fuel is forced by the accumulator, a valve commanding said opening, means for blocking the valve, operative connections between said plunger and valve to seat the same including a lever, means for periodically unblocking the valve, and valve-operating means.

5. An airless fuel injection device for internal combustion engines comprising an accumulator chamber having a fuel outlet, a valve commanding the same, an accumulator plunger mounted in the chamber side by side with the valve, operative connections between the accumulator plunger and the valve tending to seat the valve, means for blocking movement of the valve from its seat, means for periodically unblocking the valve, and valve operating means.

6. An airless fuel injection device for internal combustion engines comprising an accumulator chamber having a fuel outlet, a valve commanding the same, a lever fulcrumed on the accumulator chamber movably connected to the accumulator plunger and operatively associated with the valve to seat the same and adapted to act thereon through reduced leverage, an accumulator plunger mounted in the chamber side by side with the valve, means for blocking movement of the valve from its seat, means for periodically unblocking the valve, and valve operating means.

7. An airless fuel injection device for internal combustion engines comprising an accumulator chamber having a fuel outlet, a valve commanding the same, an accumulator plunger mounted in the chamber side by side with the valve, operative connections between the accumulator plunger and the valve tending to seat the same, said connections including a lever fulcrumed on the accumulator chamber movably connected to the accumulator plunger and extending over a part of the valve and free to move away from it, means for blocking movement of the valve from its seat, means for unblocking the valve and valve operating means.

8. In an airless fuel injection apparatus for internal combustion engines, a chamber having a fuel injection opening, a valve closing said opening, an accumulator having a plunger subject to displacement by fuel

and serving to store up energy while the valve is closed, and a lever interposed between the accumulator and the valve in a valve-closing connection by which said energy acting entirely through said lever slams the valve shut, the seating of the valve by such action serving to limit the return movement of the accumulator plunger.

9. An airless fuel injection device for internal combustion engines comprising a chamber having a fuel injection opening, a valve commanding the same, an accumulator having an accumulator spring relatively movable with respect to said valve, and a lever of the third class interposed between the accumulator and the valve, the seating of the valve by the accumulator through

said lever serving to limit the return movement of the accumulator.

10. In an airless fuel injection apparatus for internal combustion engines a chamber having a fuel injection opening, a valve closing said opening, an accumulator subject to displacement by fuel and serving to store up energy while the valve is closed, and a means for seating said valve including a lever interposed between said accumulator and valve and operatively connecting them only on the return stroke of the accumulator.

In testimony whereof, I have signed this specification.

EDUARD VON SALIS.
